UNITED STATES PATENT OFFICE.

GEORGE LOCKROW, OF MERIDEN, CONNECTICUT.

DESIGN FOR A LAMP BRACKET OR STANDARD.

SPECIFICATION forming part of Design No. 36,134, dated November 4, 1902.

Application filed August 13, 1902. Serial No. 119,580. Term of patent 7 years.

To all whom it may concern:

Be it known that I, GEORGE LOCKROW, a citizen of the United States of America, residing at Meriden, in the county of New Haven and 5 State of Connecticut, have invented a new, original, and ornamental Design for Lamp Brackets or Standards, of which the following is a specification.

As shown in the drawing, the leading or 10 material features of my design consist in a representation of a poppy-blossom and a poppy-bud supported on stems, which spring from a suitable base. This base is represented as made up of poppy-leaves, and there

are poppy-leaves on the part representing 15 the stem.

Having described my invention, what I claim as new, and desire to secure by Letters Patent, is—

The ornamental design for a lamp bracket 20 or standard substantially as shown and described.

In testimony whereof I affix my signature in presence of two witnesses.

GEORGE LOCKROW.
